(57) **ABSTRACT**

This invention relates to a new and distinct everbearing variety of blackberry plant named 'PS-BK3-17.006-13'. The new variety is primarily adapted to the growing conditions of the central coast of California and is characterized by the following: mid-season primocane production with medium sized fruit with good flesh and skin firmness. Fruit is of consistent oblong shape, with medium gloss and good flavor. Foliage is slightly convex (u-shaped) and medium green, possessing weak rugosity, weak gloss and 5-foliate leaves. Primocanes have an absent or very weak waxy coat, low thorn density of green thorns and weak anthocyanin coloration.

6 Drawing Sheets

1

Latin name of the genus and species of the plant claimed:
Rubus L. subgenus *Rubus*.

Variety denomination: 'PS-BK3-17.006-13'.

BACKGROUND OF THE INVENTION

The present invention relates to a new and distinct fall bearing blackberry plant designated as 'PS-BK3-17.006-13'. This new variety is a result of a controlled cross made in 2017 in Watsonville, Calif. between blackberry variety 'BK3 14.046-34' (unpatented) as the female parent and blackberry variety 'BK3 14.057-02' (unpatented) as the male parent in an ongoing breeding program. The variety is botanically known as *Rubus* L. subgenus *Rubus*.

The seedling resulting from the aforementioned cross was asexually propagated by dormant canes in Santa Cruz County, Calif. and was subsequently selected by the inventor from a controlled breeding plot in Watsonville, Calif. in 2019. After its selection, the new variety was further asexually propagated by dormant canes, roots and non-dormant root shoot cuttings in Santa Cruz County, Calif., San Joaquin County, Calif. and Siskiyou County, Calif. The new variety was then extensively tested over the next several years in fruiting fields in Santa Cruz County, Calif. This propagation has demonstrated that the combination of traits disclosed herein as characterizing the new variety are fixed and remain true to type through successive generations of asexual reproduction.

2

BRIEF SUMMARY OF THE INVENTION

'PS-BK3-17.006-13' is primarily adapted to the climate and growing conditions of the central coast of California. This region provides the necessary year-round temperatures required for it to produce and maintain a strong vigorous plant and to remain in fruit production from August through December on primocanes and in the ensuing year from June through August on the floricanes. The following traits have been repeatedly observed and are determined to be unique characteristics of 'PS-BK3-17.006-13', which in combination distinguish this blackberry plant as a new and distinct variety:

1. Primocane production
2. Berries with firm flesh and skin
3. Reduced thorn density
4. Fruit with strong adherence to receptacle
5. Good flavor

BRIEF DESCRIPTIONS OF THE DRAWINGS

The accompanying color photographs illustrate the overall appearance of typical specimens of the new blackberry variety, 'PS-BK3-17.006-13' at various stages of development as true as reasonably possible with color reproductions of this type. Color in the photographs may differ slightly from the color value cited in the detailed botanical descrip-

tion which accurately describes the color of 'PS-BK3-17.006-13'. The depicted plant and plant parts of the new blackberry variety 'PS-BK3-17.006-13' were taken in Watsonville, Calif. and are approximately 2 to 16 months old:

FIG. 1 shows typical floricane leaf color, foliate and rugosity characteristics of 'PS-BK3-17.006-13' taken in the month of March 2020;

FIG. 2 shows typical primocane coloration, thorn density and coloration of 'PS-BK3-17.006-13' taken in the month of October 2021;

FIG. 3 shows typical primocane flower bud and petal coloration of 'PS-BK3-17.006-13' taken in the month of September 2021;

FIG. 4 shows typical primocane fruit and drupelet characteristics of 'PS-BK3-17.006-13' taken in the month of September 2021;

FIG. 5 shows typical floricane fruit characteristics of 'PS-BK3-17.006-13' as compared to those of its parents (female on left; male on right) taken in the month of July 2021;

FIG. 6 shows typical primocane plant height and habit of 'PS-BK3-17.006-13' taken in the month of October 2021.

DETAILED BOTANICAL DESCRIPTION

'PS-BK3-17.006-13' has not been observed under all possible environmental conditions. The characteristics of the new variety may vary in detail, depending upon variations in environmental factors, including weather (temperature, humidity and light intensity), day length, soil type, and location.

The aforementioned photographs, together with the following description of the new raspberry variety 'PS-BK3-17.006-13', unless otherwise noted, are based upon observations taken during the 2020-2021 growing season in Watsonville, Calif. Primocane measurements and ratings were taken from plants of 'PS-BK3-17.006-13' produced from a tissue culture lab located in Watsonville, Calif. during the summer of 2020 and planted out mid-December 2020 into trial plots in Watsonville, Calif. The approximate age of the observed primocane plants is 6 to 10 months. Floricane measurements and ratings were taken from the previous year's trial plots of 'PS-BK3-17.006-13' planted in mid-December of 2019 and were observed at an approximate age of 16 to 18 months. Yield observations and fruit quality characteristics are averaged from three years of data collected from the 2019 through 2021 production seasons. Flower measurements and characteristics are from secondary flowers unless otherwise noted. Fruit characteristics and measurements are from secondary fruit unless otherwise noted. Foliage characteristics and measurements are from 5-foliate foliage unless otherwise noted.

Color terminology where noted follows The R.H.S. Colour Chart Sixth Edition (2019 Reprint), Royal Horticultural Society, London, United Kingdom (1966).

The following tables 3-7 describe fruit, plant, foliage, flower and pest/disease characteristics of the new blackberry 'PS-BK3-17.006-13'.

TABLE 3

FRUIT CHARACTERISTICS	
Characteristic	'PS-BK3-17.006-13'
Color mature fruit	RHS 203A Black
Fruit length (mm)	25.86

TABLE 3-continued

FRUIT CHARACTERISTICS	
Characteristic	'PS-BK3-17.006-13'
Fruit width (mm)	22.03
Length/Width ratio	1.17
Fruit predominant shape	Longer than broad
Drupelets per berry	Elliptic
Drupe length (mm)	73.8
Drupe diameter (mm)	4.75
Relative size of drupes	4.89
Fruit size	Medium
Color achenes	Medium
Seed length (mm)	RHS 162C
Seed width (mm)	Light yellow
Seed weight (mg)	3.36
Fruit per node	1.60
Abscission diameter (mm)	3.70
Abscission color	11.1
Glossiness	RHS 157A
Adherence of receptacle	Pale yellow green
Firmness of flesh	Medium
Firmness of skin	Strong
Soluble Solids (% brix)	Firm
Titratable Acidity (% as Citric Acid)	9.76
Flavor	0.96
	Good

TABLE 4

PLANT CHARACTERISTICS	
Characteristic	'PS-BK3-17.006-13'
General:	
Habit	Upright to semi-upright
Plant height (m)	2.1
Plant width (cm)	30
Time to initiate roots (days)	10-15
Canes per hill	3.6
Productivity	Medium
Self-fruitfulness	Yes
Type of bearing	On both previous season and current season canes
Primocane:	
Color (true)	RHS 144B
Length (cm)	Strong yellow green
Basal diameter (mm)	202.6
Diameter central $\frac{1}{3}$ (mm)	20.89
Lateral length at central $\frac{1}{3}$ (cm)	14.01
No. fruiting laterals per cane	38.1
Total nodes per cane	13.6
Internode length at central $\frac{1}{3}$ (mm)	28
Anthocyanin coloration	64.42
Anthocyanin intensity	RHS 181A
Pubescence	Moderate red
Vegetative bud length (mm)	Weak
Vegetative bud diameter (mm)	Present
Vegetative bud shape	4.61
Vegetative bud color	Ovate
Strength of waxy coat (glaucoosity)	RHS 144B
Time of leaf burst	Strong yellow green
Time of flowering	Absent to very weak
Time of fruiting	Medium
Length of fruiting season	Medium
% of total yield	Long

US PP34,597 P2

6

TABLE 4-continued

PLANT CHARACTERISTICS	
Characteristic	‘PS-BK3-17.006-13’
Flowering period	Late May to Late October
Harvest period	Late August to Early December
Primocane fruit weight (g)	7.35
Primocane yield (g/plant)	3,940
Young Shoots:	
Number	2-3 Few
Coloration	RHS 137C Moderate yellow green
Intensity of green	Medium
Thorns:	
Thorn presence	Present
Thorn Texture	Rigid
Thorn attitude of the tip	Downward
Thorn coloration (tip)	RHS 144B Strong yellow green
Thorn coloration (base)	RHS 144B Strong yellow green
Thorn length at central $\frac{1}{3}$ (mm)	7.04
Thorn width of base at central $\frac{1}{3}$ (mm)	5.35
Thorn density per cm at central $\frac{1}{3}$	0.81
Floricane:	
Color (true)	RHS 187B
Length (cm)	Dark red 107.22
Width at central $\frac{1}{3}$ (mm)	14.82
Cane shape in cross section	Rounded to angular
Total nodes per cane	14.1
Internode length at central $\frac{1}{3}$ (mm)	68.11
Fruiting lateral attitude	Erect to horizontal
Time of bud burst	Medium
Time of leaf burst	Medium
Time of flowering	Medium
Time of fruiting	Medium
Length of fruiting season	Medium
% of total yield	41%
Flowering period	Late April to Late June
Harvest period	Late May to Late July
Floricane fruit weight (g)	6.61
Floricane yield (g/plant)	2,738

TABLE 5-continued

FOLIAGE CHARACTERISTICS	
Characteristic	‘PS-BK3-17.006-13’ (5 Foliate)
Terminal Leaflet:	
Length (mm)	155.11
Width (mm)	102.96
10 Length/width ratio	1.50
Size	Longer than broad
Shape	Medium
Shape of tip	Ovate
Shape of base	Acuminate
Undulation of margin	Cordate
15 Shape in cross section	Weak
Presence of lobing	U-shaped
Margin: depth of incisions	Absent
Lateral Leaflet (basal pair):	4.06
20 Length (mm)	99.65
Width (mm)	59.74
Length/width ratio	1.7
Rachis length (mm)	Much longer than broad
Rachis diameter (mm)	58.91
25 Rachis anthocyanin coloration of upper surface	2.44
Rachis anthocyanin intensity	RHS 187B
Orientation	Dark red
Arrangement	Strong
Shape	Opposite
Relative position of lateral leaflets	Compound
30 Shape of the base	Ovate
Shape of the tip	Overlapping
Petiole:	
Length (mm)	121.05
Diameter (mm)	4.77
35 Thorn presence	Present
Thorn orientation	Erect
Relative number of petiole thorns	9.1
Anthocyanin coloration of petiole upper surface	RHS 187B
Anthocyanin intensity of petiole upper surface	Dark red
40 Color of stipule	Medium
Stipule length (mm)	RHS 144A
Stipule width (mm)	Strong yellow green
Stipule size	15.95
45 Stipule shape	1.41
Stipule orientation	Medium
Stipule arrangement	Subulate
	Erect
	Free

TABLE 5

FOLIAGE CHARACTERISTICS	
Characteristic	‘PS-BK3-17.006-13’ (5 Foliate)
General:	
Color of upper surface	RHS NN137A
Color of lower surface	Greyish olive green
Venetion	RHS 138A
Shape in cross section	Moderate yellowish green
Arrangement	Pinnate
Relief between veins (rugosity)	Slightly convex
Glossiness	Weak
Margins	Weak
Number of leaflets/leaf	Biserrate
Total leaf length (cm)	Five
Total leaf width (cm)	25.6

TABLE 6

FLOWER CHARACTERISTICS	
Characteristic	‘PS-BK3-17.006-13’
50 Petal color (upper surface)	RHS NN155B
Petal color (margin)	Pinkish white
55 Flower diameter (mm)	RHS 69C
Petal Length (mm)	Very pale purple
Petal width (mm)	44.16
60 Petal length/width ratio	21.63
Petal shape in cross section	13.66
Petal shape (overall)	1.58
Petal shape (apex)	Longer than broad
Petal shape (base)	Flat
65 Petal margin	Obovate
	Obtuse
	Crenate

US PP34,597 P2

TABLE 6-continued

FLOWER CHARACTERISTICS	
Characteristic	'PS-BK3-17.006-13'
Petal texture	Glabrous
No. petals/flower	5.0
No. sepals/flower	5.0
Sepal length (mm)	9.65
Sepal width at base (mm)	6.40
Sepal shape	Widely deltate
Sepal shape (apex)	Acuminate
Sepal coloration (upper surface)	RHS 143C
Sepal coloration (lower surface)	Strong yellow green RHS 142C
Sepal margin	Entire
Sepal texture	Pubescent
No. stamen/flower	115
Filament length (mm)	5.87
Filament color	RHS 155C
Pollen quantity	Greenish white
Pollen color	High RHS 155B
Anther length (mm)	1.11
Anther diameter (mm)	0.50
Anther coloration (pre-dehiscence)	RHS 155C
Anther coloration (post-dehiscence)	Greenish white RHS 165A
Stigma shape	Moderate brown
Stigma length (mm)	Lobed
Stigma diameter (mm)	0.11
Pedicle length (mm)	0.42
Pedicle diameter (mm)	22.89
Pedicle coloration	0.98
Pedicle anthocyanin coloration	RHS 144B
Pedicle anthocyanin intensity	Strong yellow green
Relative number of pedicel thorns	RHS 181D
Peduncle anthocyanin presence	Dark yellowish pink
Peduncle anthocyanin coloration	Absent to very weak
Peduncle anthocyanin intensity	1.8
Peduncle length (mm)	Few
Peduncle diameter (mm)	Present
Relative number of peduncle thorns	RHS 184C
Peduncle thorn length (mm)	Moderate purplish red
Peduncle thorn width at base (mm)	Absent to very weak
	88.42
	3.11
	4.2
	4.67
	2.39

COMPARISON WITH PARENTAL AND COMMERCIAL VARIETIES

‘PS-BK3-17.006-13’ differs from the proprietary female parent ‘BK3 14.046-34’ (unpatented) in that ‘PS-BK3-25 17.006-13’ has slightly larger, less narrowly oblong fruit shape, smaller drupelet size, a more upright plant habit and later fruit production.

‘PS-BK3-17.006-13’ differs from the proprietary male parent ‘BK3 14.057-02’ (unpatented) in that ‘PS-BK3-30 17.006-13’ has a less round fruit shape, glossier berries, sweeter flavor and a larger overall primocane yield.

‘PS-BK3-17.006-13’ differs from the commercial variety ‘APF-45’ (patented, U.S. Plant Pat. No. 22,449) in that ‘PS-BK3-17.006-13’ has a smaller, less glossy berry with 35 smaller seeds and sweeter flavor. ‘PS-BK3-17.006-13’ also has a slightly less upright habit, less overall vigor with both fewer and smaller thorns than ‘APF-45’.

For identification, a series of molecular markers have been determined for this new variety.

40 I claim:

1. A new and distinct variety of blackberry plant named ‘PS-BK3-17.006-13’, substantially as illustrated and described herein.
